CLAIM

The ornamental design for an extension handle, as shown
and described.

DESCRIPTION

FIG. 1 is a front, top perspective view of an extension handle
according to the present disclosure;

FIG. 2 is a rear, bottom perspective view of the extension
handle of FIG. 1;

FIG. 3 is a first side view of the extension handle of FIG. 1;

FIG. 4 is a second, opposite side view of the extension
handle of FIG. 1;

FIG. 5 is a front view of the extension handle of FIG. 1;
FIG. 6 is a rear view of the extension handle of FIG. 1;
FIG. 7 is a top view of the extension handle of FIG. 1; and,
FIG. 8 is a bottom view of the extension handle of FIG. 1.
The broken lines in the drawings illustrate boundaries that
form no part of the claimed design.
